(57) **CLAIM**

The ornamental design for a medical apparatus for imaging having an ornamentation, as shown and described.

DESCRIPTION

FIG. 1 is a front elevational view of a medical apparatus for imaging having an ornamentation showing our new design; FIG. 2 is a back elevational view thereof; FIG. 3 is a top plan view thereof; FIG. 4 is a bottom plan view thereof; FIG. 5 is a right side elevational view thereof; FIG. 6 is a left side elevational view thereof; FIG. 7 is a perspective view taken generally from the upper, front, right-hand side thereof; and, FIG. 8 is an enlarged front elevational view of the ornamentation shown without the medical apparatus for imaging. The broken lines illustrate portions of the medical apparatus for imaging having an ornamentation that form no part of the claimed design.
